(57) **CLAIM**

The ornamental design for a combined radio tuner, remote controller and recording unit, as shown and described.

DESCRIPTION

FIG. 1 is a perspective view of a combined radio tuner, remote controller and recording unit, showing my new design;

FIG. 2 is a right side view thereof;

FIG. 3 is a perspective view of the main body, shown separately for clarity of illustration;

FIG. 4 is a right side view thereof;

FIG. 5 is a left side view thereof;

FIG. 6 is a front view thereof;

FIG. 7 is a back view thereof;

FIG. 8 is a left end view thereof;

FIG. 9 is a right end view thereof;

FIG. 10 is a right side view of one connector, shown separately for clarity of illustration, the left side, top and bottom views being identical thereto;

FIG. 11 is a right end view thereof;

FIG. 12 is a left end view thereof;

FIG. 13 is a right side view of the other connector, shown separately for clarity of illustration;

FIG. 14 is a left side view thereof;

FIG. 15 is a front view thereof;

FIG. 16 is a back view thereof;

FIG. 17 is a bottom end view thereof; and,

FIG. 18 is a top end view thereof.

The bracketed portions shown in FIGS. 1 and 2 indicate indeterminate length.
